UNITED STATES PATENT OFFICE

WALLACE E. GARVEY, OF SALEM, NEW JERSEY, ASSIGNOR TO SALEM GLASS WORKS, OF SALEM, NEW JERSEY, A CORPORATION OF NEW JERSEY

DESIGN FOR A JAR OR SIMILAR CONTAINER

Application filed March 31, 1932. Serial No. 43,339. Term of patent 3½ years.

To all whom it may concern:

Be it known that I, WALLACE E. GARVEY, a citizen of the United States, residing at Salem, county of Salem, and State of New Jersey, have invented a new, original, and ornamental Design for a Jar or Similar Container, fully described and represented in the following specification and the accompanying drawings, forming a part of the same, in which:

Figure 1 is a front elevation of a jar or similar container showing my new design; and

Figure 2 is a sectional view taken on the line 2—2 of Figure 1.

I claim:

The ornamental design for a jar or similar container, as shown.

WALLACE E. GARVEY.
